UNITED STATES PATENT OFFICE

2,165,243

WATER CLOSET

Sven Duner, Wheaton, Ill., assignor to Duner Co.,
Chicago, Ill., a corporation of Illinois

Application December 18, 1936, Serial No. 116,568

4 Claims. (Cl. 4—76)

This invention relates in general to improvements in water closets and has more particular reference to the type of water closet in use in vehicles.

5 A principal object of the invention is the provision of a water closet adapted for use in moving vehicles of lighter construction where a savings in weight is desired, as in the case of the new type construction of streamline trains, busses and 10 trailers.

An important object of the invention is the provision of a water closet for vehicles which is much more simple in structure and more easily adapted for assemblage than those of the prior 15 art.

Heretofore, it has been found necessary to construct the water closets for railways, trailers, busses and the like in several pieces which are then assembled. The assembled unit was necessarily very heavy as the outer supporting member was usually cast of metal, while the bowl or hopper was made of porcelain. This was satisfactory in the older style of railway coaches where the weight of the water closet was not considered as being excessive and did not materially affect the speed and operation of the train. But in the present era, the railways have come to the conclusion that weight is a necessary factor to be considered, and they have increased the speed 20 and efficiency of operation by lightening the trains, streamlining, and the like, and the weight of water closets has become an important item. The same factors obtain in the modern busses and trailers. Therefore, the instant invention contemplates the provision of water closets that are much lighter in construction, without sacrificing any of the important features of the prior art 25 water closets.

Another important object of the invention is 30 the provision of such a light weight water closet in which the same operating mechanism heretofore employed may be interchangeably used.

Numerous other objects and advantages of the invention will be apparent as it is better understood from the following description, which, when taken in connection with the accompanying drawings, discloses a preferred embodiment thereof.

In the drawings:

Figure 1 is a side elevational view of a water 50 closet embodying the features of the invention; and

Fig. 2 is a vertical sectional view taken substantially on line 2—2 in Fig. 1.

Referring more particularly to the drawings, 55 reference numeral 11 indicates in general a water

closet or hopper comprising a bowl 12 and a stand or supporting portion 13 formed integrally therewith. By making the bowl and stand in one piece, a very much lighter water closet results, without sacrificing any of the advantages of the prior art 5 water closets of this type. The bowl 12 and stand 13 are preferably molded from vitreous china, porcelain, or the like, although a thin metal casting may be employed.

A dump pan 14 normally closes the lower end 10 of the bowl 12, as shown in Fig. 2, and is fixedly mounted on a transverse shaft 15 extending through and suitably journaled in the side walls of the stand portion 13 of the water closet 11. The dump pan 14 and operating mechanism 15 therefor will be briefly described herein, a more complete and detailed description of similar mechanism being given in United States Letters Patent Nos. 1,831,528; 1,845,252; 1,898,656; 1,898,657, and 1,992,653. 20

An arm 16, fixedly secured to the shaft 15 at one end, is provided with a pin 17 extending into a slot 18 which is provided in the lower portion of a link 19. The opposite end of the shaft 15 is equipped with an arm 21 carrying at its free end 25 a counterweight 22 for normally holding the dump pan 14 in closed position, as shown in Fig. 2.

The upper end of the link 19 is pivotally connected at 23 with a lever 24 having a handle 25 30 at one end and being connected at the other or fulcrum end with a flushing valve 26 of any preferred or desired construction, so that upon raising the lever 24, the movement of the dump pan 14 to open position is initiated while at the same 35 time the flushing valve 26 is set in operation in order to thoroughly flush the interior of the bowl 12.

Within the lower end of the stand portion 13 directly below the bowl 12 and dump pan 14 is 40 positioned a funnel-shaped, downwardly extending member 27 (Fig. 2). The member 27 is detachably associated with the stand 15 so that the dump pan 14 is easily accessible, either for repairs or removal. The upper flaring edge 28 of the 45 member 27 abuts against a shoulder 29 formed within the interior of the stand portion 13. A non-soluble cement or putty 31 is used to make the joint between the upper end of the member 27 and the shoulder 29 water tight and prevent any 50 seepage therethrough. Cast integrally with the member 27, near its converging end, is an outwardly disposed, annular flange 32. A rubber gasket 33 is inserted between the flange 32 and the lower portion of the stand 13 to provide a 55

5 cushion-like mounting for the water closet 11 when the same is installed in a railway coach or other moving vehicle. A number of bolts 34 secure the flange 32 and the stand 13 together so that the closet 11 may be moved as a single unit. The entire unit may be fastened to the floor or other supporting means by suitable bolts 35.

10 A pair of oppositely disposed bearing members 36 and 37 are cast integrally with the member 27. A shaft 38, journaled in the bearing 36, carries an arm 39 fixed thereto at one end, and an arm 41 loosely mounted thereon, the latter having a bifurcated end 42 which loosely supports it on the shaft 38. The other end of the arm 41 is yieldingly connected to the fixed arm 39 by means of a coiled tensioned spring 43. A pin 44 projecting laterally from the arm 41 between its ends serves as a pivotal support for a lever 20 45 which carries a weight 46 equipped at its lower portion with a knob 47 of rubber, or other suitable shock absorbing material.

25 A finger 48 projecting upwardly from the lever 45 supports at its free end an adjusting element or screw 49 extending through a tapped opening of the finger 48 against a lug or abutment 51 which projects laterally from the arm 39. The screw 49 is held in adjusted position relatively to the finger 48 by means of a nut 52.

30 Extending inwardly from the weight 46 is a pin 53 which is adapted to travel in a slot 54 formed in a link 55 which is pivotally secured at 56 to a segment lever arm 57. The outer periphery of the segment lever arm 57 is in the 35 shape of an arc of a circle having its center at the center of the shaft 15. The segment lever arm 57 is adapted to come in contact with a small roller 58 (Fig. 2) attached to the fixed arm 39, and is fixedly mounted to the shaft 15 by 40 means of a coupling lever 59.

45 Journaled in the bearing 37 is a shaft 61 which has fastened to it at its outer end an arm 62, which in turn is fastened to a weight 63 similar in size to the weight 46. Fastened to the inner end of the shaft 61 and disposed interiorly of the stand portion 13 is a downwardly extending arm 64, and a corresponding arm 65 is also fastened to the interior end of the shaft 38. The lower ends of the arms 64 and 65 are 50 in turn fastened to a draft member or sealing plate 66 which is adapted to close the lower open end of the member 27.

55 The draft plate 66 is normally held in a partially open position so as to prevent freezing thereof to the lower end of the member 27 when the closet 11 is used in cold weather. However, when the lever 25 and the lever arm 24 is pressed downwardly, the segment lever 57 comes into contact with the roller 58. The initial movement of the segment lever 57 causes a movement of the arm 45, and this in turn causes the shafts 38 and 61 to rotate and thus close the draft plate 66. Upon the continued downward movement of the lever 24 the dump pan 14 is moved away from the opening in the bowl 12. Upon 60 return to normal position of the lever 24 the dump pan 14 again closes the opening in the bowl 12 and the draft plate 66 opens to allow the refuse to be emptied.

65 70 By casting the bowl 12 and stand portion 13 integrally, a much lighter structure is provided

than those employing a separate bowl and stand, as shown in the patents above referred to. The necessity for additional securing means, such as is disclosed in U. S. Letters Patent No. 1,711,635, is also eliminated, while permitting ready removal of the water closet for cleaning or repair service. The light weight construction thus provided, together with the novel cushioned mounting therefor results in a water closet which is particularly adapted for use in vehicles, especially those in which weight is of primary importance.

10 It is thought that the invention and many of its attendant advantages will be understood from the foregoing description, and it will be apparent 15 that various changes may be made in the form, construction and arrangement of the parts without departing from the spirit and scope of the invention or sacrificing all of its material advantages, the form hereinbefore described being 20 merely a preferred embodiment thereof.

I claim:

1. A water closet, comprising a bowl having a lower open end, a stand portion formed integrally with said bowl for supporting the same and having a lower open end, a dump pan mounted in said stand portion adjacent the lower open end of said bowl, and a closure member mounted in the lower open end of said stand portion and adapted to be removed therefrom to provide access to said dump pan.

2. A water closet, comprising a bowl having a lower open end, a stand portion formed integrally with said bowl for supporting the same and having an open lower end, a dump pan mounted in 35 said stand portion adjacent the lower open end of said bowl, and a separate closure and discharge member removably mounted in the lower open end of said stand portion.

3. A water closet, comprising a vitreous bowl 40 having a lower open end, a stand portion, said stand portion formed integrally with said bowl for supporting the same and having a lower open end with a supporting flange portion, a dump pan mounted in said stand portion adjacent the 45 lower open end of said bowl, a hollow metallic discharge member removably mounted adjacent the lower open end of said stand portion and having a flange portion formed integrally therewith and disposed below the flange portion of 50 the lower open end of said stand portion, and a draft plate mounted adjacent the lower open end of said discharge member.

4. A water closet, comprising a vitreous bowl 55 having a lower open end, a stand portion formed integrally with said bowl for supporting said bowl and having a lower open end with a supporting flange portion, a dump pan mounted in said stand portion adjacent the lower open end of said bowl, a hollow metallic discharge member 60 removably mounted adjacent the lower open end of said stand portion and having a flange portion formed integrally therewith disposed below the supporting flange portion of the lower open end 65 of said stand portion, said hollow metallic discharge member being removable to provide ready access to said dump pan, and a draft plate mounted adjacent the lower open end of said hollow metallic discharge member.
